ROOFING CLIP

Waldemar Kroier, Jacksonville, Fla.

Application July 9, 1947, Serial No. 759,744

10 Claims. (Cl. 108—18)

1

The present invention relates to metal roofing and more particularly to improved means for securing ribbed roofing sheets to supporting members such as purlins, beams, rafters and the like.

An important object of the invention consists in providing an improved clip structure over what is embodied in my Patent 2,360,879, dated October 24, 1944. While the two-piece clip disclosed in this patent has proved satisfactory, it has been found that when the continuous side flanges of the clip interlock with the indentations in the side walls of the ribs they do not provide positive means for preventing displacement or movement of the sheets relative to the clip. In order to overcome this disadvantage, the improved clip is preferably formed in one piece and has a longitudinal portion or limb extending into the ribbed or corrugated portion of the roofing sheet. The limb is provided with laterally extending interrupted flanges projecting alternately from opposite sides thereof so as to engage the interlocking indentations in the roofing sheet in order to prevent displacement or longitudinal and transverse movement of the roofing sheet relative to the clip when the parts are set up.

Another object of the invention consists in providing a substantially U-shaped clip for securing roofing sheets to purlins or beams, in which one of the limbs of the clip has its upper edge provided with laterally extending interrupted flanges projecting alternately from opposite sides thereof so as to engage the interlocking indentations in the roofing sheet, and in which means in the form of laterally extending offset flanges project from opposite sides of either the lower edge of the upper limb of the U-shaped clip or from the upper edge of the lower limb so as to constitute stabilizing, lateral projections which engage the supporting member in order to maintain the clip firmly in a balanced position.

Other objects and advantages of the invention will become apparent from the following description when taken in conjunction with the accompanying claims and drawings.

Referring to the drawings in which are shown several preferred embodiments the invention may assume:

Figure 1 is a sectional view of a ribbed roofing structure constructed in accordance with the present invention.

Figure 2 is a detailed perspective view of the clip shown in Figure 1.

Figure 3 is a sectional view taken substantially along the line 3—3 of Figure 1.

2

Figure 4 is a plan view of Figure 1.

Figure 5 is a sectional view similar to Figure 1 of a modified form of the invention.

Figure 6 is a perspective view of the clip shown in Figure 5.

Figure 7 is a sectional view similar to Figure 1 of a further modified form of the invention.

Figure 8 is a perspective view of the clip shown in Figure 7, and

10 Figure 9 is a sectional view similar to Figure 3 showing nested ends of adjacent roofing sheets connected to the clip.

Referring to Figures 1 to 4 of the drawings, 10 indicates a metal roofing sheet having one or 15 more longitudinally extending continuous ribs or raised portions 11, 12 and 13 (Fig. 4). Preferably the side walls of the center rib 12 are provided with spaced interlocking indentations 14 (Fig. 3), which are formed by any suitable means, such as 20 the roofing tool shown in the above referred to Patent 2,360,879, and in the manner and for the purpose hereinafter described.

In order to firmly secure the roofing sheet 10 to a supporting member such as a purlin, beam or 25 the like, so as to prevent displacement of the sheet relative to the supporting member, a new and improved one-piece clip is provided which may assume various sizes and shapes in accordance with the type of building structure which it is to be 30 associated. As particularly shown in Figures 1 and 2, the clip is in the form of a substantially U-shaped flat metal member 15 having an upper limb or arm 16 and a spaced lower limb 17 (Fig. 2). The limbs 16 and 17 are arranged to overlap 35 and engage any suitable fixed supporting member such as a wooden purlin or beam 18 (Fig. 1). The limb 16 at its upper edge is provided with laterally extending interrupted flanges or lugs 19 that form longitudinally spaced recesses 20 on each side of 40 the limb so that the flanges 19 and recesses 20 project alternately from opposite sides of the clip and preferably extend the length of the limb 16. The limb 16 is inserted into the center rib 12 and the roofing tool applied to the center rib so as 45 to form the spaced indentations 14 (Fig. 4) and also to crimp opposite sides of the ribs inwardly towards each other as at 6 (Fig. 3). During this operation, the portions of the rib 12 adjacent the flanges 19 are rounded or curved as at 7 and merged into the adjacent crimped portion 6, while the opposite side 8 of the rib adjacent the recess 20 forms an acute angle with the crown or top of the rib. The roofing tool also crimps the crown 55 of the rib inwardly as at 9 so that the parts assume

the position as shown in Figure 3 in order to firmly secure the roofing sheet to the clip by a tenacious and strong positive connection.

The lower edge of the limb 16 may also be formed with offset laterally extending flanges 21 which project outwardly therefrom so as to engage and rest firmly on the upper surface of the beam 18 and provide stabilizing means for properly balancing and maintaining the clip 15 and its associated parts in firm contact with the beam.

In the modification shown in Figures 5 and 6 the parts are substantially similar to the form previously described, and the U-shaped clip 22 is constructed so as to secure the longitudinal rib 23 of roofing sheet 24 to a metal angle bar or the like 25. The horizontal arm 26 of the bar 25 may taper outwardly and in order that the spaced limbs 27 and 28 of the clip 22 may snugly engage the arm 26, the clip 22 is formed with a complementary tapered opening 29 into which the arm 26 extends. The upper limb 27 of the clip 22 has laterally extending interrupted lugs 30 and recesses 30' that project alternately from opposite sides thereof so as to engage the interlocking indentations in the sides of the rib in a manner similar to the flanges 19 previously described. The lower limb 28 of the clip 22 may have at its upper edge laterally offset flanges 31 and 32 arranged to engage the underside of the arm 26 of the angle bar so as to provide a stabilizing seat for maintaining the clip firmly in position.

In the modification shown in Figures 7 and 8, the clip 33 has a horizontal limb 34 and a depending limb or arm 35 which extends downwardly from one end of the limb 34 so as to be of substantially L-shaped construction. The limb 34 is formed with laterally extending interrupted flanges 36 which project outwardly from the upper edge thereof and with stabilizing flanges 37 and 38 that are offset relative to each other and extend from the lower edge of the limb 34. The depending limb 35 of the clip 33 is formed with spaced parallel continuous flanges 39 and 40 having aligned openings 41. The L-shaped clip 33 is interposed between the roofing sheet 42 and the rib 43 so that the flanges 36 on the limb 34 interlock with the indentations formed in the sides of the rib 43 in the manner as previously described. The depending limb 35 is positioned to engage the vertical side 44 of a purlin or beam 45 and is secured thereto by the nail 46 which extends through the openings 41 in the flanges 39 and 40.

In the modified form of the invention shown in Figure 9, the roofing sheet 48 has a ribbed or raised end 49 arranged to interfit with a complementary formed rib 50 on the end of an adjacent roofing sheet 51 so as to provide a nesting rib structure. The overlapped nested ends of the adjacent sheets 48 and 51 are interlocked by forming indentations in the sides of the nested ribs similar to the indentations 14, by a roofing tool such as disclosed in my Patent 2,360,879. The overlapped nested portions of the roofing sheets may be connected to a purlin, beam or the like by any one of the clips previously referred to. As shown, clip 15 is connected to a beam 52 and the limb 16 thereof is inserted in the overlapped nested ribs of the sheets 48 and 51 so that upon forming the crimps 53 in the sides of the nested ribs, the flanges 19 and recesses 20 on the limb 16 interlockingly engage the ribs in substantially the same manner as the single sheet connection shown in Figure 3. The stabilizing limbs 21 on

the lower end of the limb 16 rest on the top of the beam 52 so as to properly balance the clip 15 when the parts are set up.

It will be noted that in all forms of the invention shown, the clip is made of one piece and is provided with laterally extending interrupted flanges and recesses between the flanges so that the flanges interlockingly engage the ribbed roofing sheet and the recesses co-act with the flanges 5 to prevent displacement of the roofing sheet or sheets relative to the clips and the supporting members when the parts are assembled. Thus simple, efficient and economical means are provided for connecting one or more roofing sheets 10 to supporting members in a firm and positive manner, and which overcomes a defect in this type of connection in which continuous flanges are used to interlock ribbed sheets to a connecting member, and which it has been found not infrequently 15 allows displacement of the roofing sheets relative to the supporting members, with the result that the efficiency and durability of the roofing structure is seriously impaired since such displacement causes leakage and rattling of the roof when subjected to vibrations or high winds and storms.

It is to be understood that the forms of the invention shown and described are merely illustrative of preferred embodiments and such changes are contemplated as come within the purview of one skilled in the art and the scope of the appended claims.

I claim:

1. A clip for securing a roofing sheet to a supporting member, said clip being of substantially U-shape and having one limb for engaging the roofing sheet, said limb having laterally extending interrupted flanges projecting alternately from opposite sides of the upper edge thereof

40 to interlockingly engage indentations on the roofing sheet, and laterally offset stabilizing flanges projecting from the lower edge of the limb to engage the supporting member.

2. A clip for securing a roofing sheet to a supporting member, said clip being of substantially U-shape and having one limb for engaging the roofing sheet, said limb having laterally extending interrupted flanges projecting alternately from opposite sides thereof to interlockingly en-

50 gage indentations on the roofing sheet to prevent longitudinal and transverse movement of the clip relative to the sheet, and a second limb provided with stabilizing lateral projections extending from opposite sides thereof to engage the supporting member.

3. A clip for securing a roofing sheet to a supporting member, said clip including a longitudinal limb and a depending limb, said longitudinal limb having laterally extending interrupted flanges projecting alternately from opposite sides thereof to interlockingly engage indentations on the roofing sheet, said depending limb having spaced parallel flanges provided with transversely aligned openings, and retaining means extending through said openings and arranged to engage the side of the supporting member for securing the clip thereto.

4. A roofing structure of the class described including in combination a sheet having an elongated rib, said rib having interlocking indentations in the side walls thereof, a supporting member, and a clip for connecting the roofing structure to the supporting member, said clip having a limb extending into the rib, said limb being 70 provided with laterally extending interrupted

flanges projecting alternately from opposite sides thereof to engage said indentations, said flanges forming spaced longitudinally disposed recesses on opposite sides of the limb for receiving portions of the indentations in the side walls of the rib to prevent longitudinal or transverse displacement of the roofing sheet relative to the clip.

5. A roofing structure of the class described including in combination a sheet having an elongated rib, said rib having interlocked indentations in the side walls thereof, a supporting member, a substantially U-shaped clip for connecting the roofing structure to the supporting member, said clip having one limb extending into the rib and provided with laterally extending interrupted flanges projecting alternately from opposite sides thereof to engage said indentations, said flanges forming spaced longitudinally disposed recesses on opposite sides of the limb for receiving portions of the indentations between the flanges so as to prevent longitudinal or transverse displacement of the roofing sheet relative to the clip, and said clip having a second limb engaging the underside of the supporting member.

6. A roofing structure of the class described including in combination a sheet having an elongated rib, said ribs having interlocked indentations in the side walls thereof, a supporting member, a substantially U-shaped clip for connecting the roofing structure to the supporting member, said clip having one limb extending into the rib and provided with laterally extending interrupted flanges projecting alternately from opposite sides thereof to engage said indentations, said flanges forming spaced longitudinally disposed recesses on opposite sides of the limb for receiving portions of the indentations between the flanges so as to prevent longitudinal or transverse displacement of the roofing sheet relative to the clip, and said clip having a second limb engaging the underside of the supporting member, one of said limbs having laterally offset stabilizing projections engaging said supporting member for maintaining the clip firmly in position.

7. A roofing structure of the class described including in combination overlapped sheets having ribs nested together, said ribs having interlocked indentations in the side walls thereof, a supporting member, a substantially U-shaped clip for connecting the roofing structure to the supporting member, said clip having one limb extending into the nested ribs and provided with laterally extending interrupted flanges projecting alternately from opposite sides thereof to engage said indentations, said limb having laterally offset stabilizing flanges projecting from opposite sides of the lower edge thereof and arranged to engage said supporting member, said flanges forming spaced longitudinally disposed recesses on opposite sides of the limb for receiving portions of the indentations between the flanges so as to prevent longitudinal or transverse displacement of the roofing sheet relative to the clip, and said clip having a second limb engaging the underside of the supporting member.

8. A roofing structure of the class described including in combination a sheet having an elongated rib, said rib having interlocked inden-

tations in the side walls thereof, a supporting member, a substantially U-shaped clip for connecting the roofing structure to the supporting member, said clip having one limb extending into the nested ribs and provided with laterally extending interrupted flanges projecting alternately from opposite sides thereof to engage said indentations, said flanges forming spaced longitudinally disposed recesses on opposite sides of the limb for receiving portions of the indentations between the flanges so as to prevent longitudinal or transverse displacement of the roofing sheet relative to the clip, and said clip having a second limb engaging the underside of the supporting member, said second limb having laterally offset stabilizing flanges projecting from the upper edge thereof and arranged to engage the supporting member.

9. A roofing structure of the class described including in combination a roofing sheet having a longitudinal rib, the side walls of said rib having interlocking indentations therein, a supporting member spaced below said roofing sheet, a substantially L-shaped clip having its horizontal limb extending into said rib and provided with laterally extending interrupted flanges projecting alternately from opposite sides thereof to engage said indentations, said flanges forming spaced longitudinally disposed recesses on opposite sides of said limb for receiving portions of the indentations in the side walls of the rib to prevent displacement of the roofing sheet relative to the clip, said clip having its depending limb engaging a side of the supporting member and provided with spaced parallel continuous flanges having aligned openings, and retaining means extending through said openings into said supporting member for securing the clip thereto.

10. A roofing structure of the class described including in combination overlapped sheets having ribs nested together, said ribs having interlocked indentations in the side walls thereof, a supporting member, a substantially U-shaped clip for connecting the roofing structure to the supporting member, said clip having one limb extending into the nested ribs and provided with laterally extending interrupted flanges projecting alternately from opposite sides thereof to engage said indentations, said flanges forming spaced longitudinally disposed recesses on opposite sides of the limb for receiving portions of the indentations between the flanges so as to prevent longitudinal or transverse displacement of the roofing sheet relative to the clip, and said clip having a second limb engaging the underside of the supporting member, one of said limbs having laterally offset stabilizing projections engaging said supporting member for maintaining the clip firmly in position.
